UNITED STATES PATENT OFFICE.

ARTHUR T. BRITTON, OF SAN JOSE, CALIFORNIA.

DESIGN FOR A WASHING-MACHINE CASING.

Application filed October 20, 1928. Serial No. 28,576. Term of patent 3½ years.

To all whom it may concern:

Be it known that I, ARTHUR T. BRITTON, a citizen of the United States, residing at San Jose, in the county of Santa Clara and State of California, have invented a new, original, and ornamental Design for Washing-Machine Casings, of which the following is a specification, reference being had to the accompanying drawing, forming a part thereof.

Figure 1 is a plan view of a washing machine casing, showing my new design.

Figure 2 is a front elevation of the same.

Figure 3 is a rear elevation of the same.

I claim:

The ornamental design for a washing machine casing, as shown.

ARTHUR T. BRITTON.
